UNITED STATES PATENT OFFICE.

JACK KATZ, OF NEW YORK, N. Y.

DESIGN FOR A BOOK END.

Application filed January 7, 1925. Serial No. 11,953. Term of patent 3½ years.

To all whom it may concern:

Be it known that I, JACK KATZ, a citizen of the United States, residing at New York, in the county of New York and State of New York, have invented a new, original, and ornamental Design for Book Ends, of which the following is a specification, reference being had to the accompanying drawing, forming part thereof.

Fig. 1 is a front view.

Fig. 2 is an edge view.

I claim:

The ornamental design for a book end, as shown.

JACK KATZ.
